SLIVER BALLING MACHINE

Gordon Fraser, Norman Fraser, and John Fraser,
Arbroath, Angus, ScotlandOriginal application June 1, 1933, Serial No.
673,892. Divided and this application November
22, 1933, Serial No. 699,250. In Germany
January 12, 1933

1 Claim. (Cl. 19—158)

This invention relates to sliver balling machines of the type in which the sliver ball or roll is wound on retractable arbor sections carried by pivoted arms jointly movable about a common axis parallel to the axes of the arbor sections so as to swing upwards in the formation of the ball, as described, for example, in the specification of Letters Patent No. 1,791,076 dated 3rd February, 1931.

10 In the machine according to the invention which is a division of our prior application Ser. No. 673,892 filed 1st June, 1933, the sliver ball is confined during its formation by non-rotatable cheek-plates, embraced by the arms, said cheek plates being relatively immovable but being arranged to rise and fall together with the arbor sections, and to release the ball on retraction of the arbor sections.

15 The figure of the accompanying drawing is a side elevation of a sliver-roll-forming or balling machine according to the invention.

20 As will be understood from reference to the drawing, the sliver ball or roll 8 is built up between a pair of spaced non-rotatable cheek plates 13 which rise and fall together with the arbor sections 1.

25 The cheek plates 13 are constituted by a frame interposed between the arbor-carrying arms 2 and fixed to the hinged cross bracket 14 to which the arbor-carrying arms 2 are pivoted, the cheek plates 13 being formed with aligned apertures 15 for penetration by the arbor sections 1.

30 During roll-building the cheek plates 13 rise with the arms 2, and, when the arbor sections 1 are withdrawn from the ball or roll 8 on completion of the latter, the combined weight of the cheek plates 13 and arms 2 causes the frame to descend and overcomes the slight friction holding the ball or roll 8 between the cheek plates 13.

35 40 The driving roller, assisted by a cross bar 16 hereinafter described and engaging the rear of the roll 8, effects automatic ejection of the ball 8 from between the cheek plates 13, tending to roll the ball out from beneath.

The cross bar 16 is arranged above the cheek plates 13 the operation being such that, in the descent of the cheek plate frame, the cross bar 16 engages the periphery of the ball or roll 8 at the rear thereof so as, in conjunction with the driving roller, to effect ejection of the ball.

As shown the cross bar 16 is attached to the upper end of a lever 22 pivoted at 23 at its lower end to the gable frame 5 of the machine and operatively connected by a link 24 to an arm 25 unitary with the cross bracket 14, the arrangement being such that, in the descent of the arms 2, the path of the cross bar 16 will be as indicated at 16—16².

When the ball is being ejected, incoming sliver 15 17 from the sliver delivery rollers 18, 19 enters a reservoir 20 bounded by the cheek plates 13, so that momentarily, while ejection is taking place, surplus sliver is caught in the reservoir 20 and effectively gripped between the arbor-sections 1 20 when they close for a re-start. 21 denotes a sliver guide.

What we claim is:—

A sliver balling machine comprising retractable arbor sections on which the ball is wound, a hinged cross-bracket, arms pivoted to said cross-bracket and carrying said arbor sections, said arms being jointly movable about a common axis parallel with the axes of said arbor sections, non-rotatable cheek-plates fixed to said cross-bracket 30 and embraced by said arms, said cheek-plates being relatively immovable but being arranged to rise and fall together with said arbor sections, said cheek-plates serving to confine the ball during its formation and releasing the ball on retraction of said arbor sections, an arm unitary with said cross-bracket, an ejector for ejecting the finished ball from between said cheek-plates, and link and lever mechanism connecting said ejector to said arm. 40
